United States Patent Office

Des. 178,563
Patented Aug. 21, 1956

178,563

TABLE LAMP

Charles W. Clemens, Nashville, Tenn., assignor to Aladdin Industries, Incorporated, Nashville, Tenn., a corporation of Illinois

Application August 18, 1955, Serial No. 37,548

Term of patent 3½ years

(Cl. D48—20)

FIG. 1.

FIG. 2.

FIG. 3.

Fig. 1 is a front perspective view of a table lamp embodying my new design;

Fig. 2 is a side view thereof taken from the left side of Fig. 1, the shade being omitted for convenience of illustration; and

Fig. 3 is a sectional view taken along the line 3—3 in Fig. 2.

The dominant features of my design are shown in solid lines.

I claim:

The ornamental design for a table lamp, substantially as shown and described.
